(57) **CLAIM**

The ornamental design for a haemorrhoid ligation instrument, as shown and described.

DESCRIPTION

FIG. 1 is a perspective view of a haemorrhoid ligation instrument showing my new design;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a top plan view thereof;

FIG. 7 is a bottom plan view thereof;

FIG. 8 is a left side elevational view thereof;

FIG. 9 is a perspective view of a ligation applicator showing my new design with the haemorrhoid instrument shown removed;

FIG. 10 is a right side elevational view thereof;

FIG. 11 is a top plan view thereof

FIG. 12 is a left side elevational view thereof;

FIG. 13 is a bottom plan view thereof;

FIG. 14 is a front plan view thereof; and,

FIG. 15 is a rear elevational view thereof.

The portions in FIGS. 1-8 that are in broken lines are not a part of the claimed invention.
